ATTORNEY

UNITED STATES PATENT OFFICE.

HEYMAN BLOCH, OF NEW YORK, N. Y., ASSIGNOR TO HIMSELF AND JULIUS FRANKENSTEIN, OF SAME PLACE.

GRATER.

SPECIFICATION forming part of Letters Patent No. 307,742, dated November 11, 1884.

Application filed February 1, 1884. (No model.)

To all whom it may concern:

Be it known that I, HEYMAN BLOCH, of the city of New York, in the county and State of New York, have invented a new and Improved 5 Grater, of which the following specification is a full, clear, and exact description.

This invention relates to a new grater with two indented surfaces adapted to grate finer and coarser articles.

10 The invention consists, principally, in the combination of a finer convex indented grating-plate with a coarser straight indented grating-plate, combined to form one grater.

The invention also consists in the details of 15 improvement hereinafter more fully pointed out.

In the accompanying drawings, Figure 1 is a back view of my improved grater. Fig. 2 is a longitudinal central section on the line x 20 x , Fig. 1; and Fig. 3, a transverse section on the line y y , Fig. 1.

The letter a represents the usual convex indented plate, provided with small apertures and converging cutters to form a grater. b 25 is the back of plate a , made preferably with flanged edges, that are bent over and soldered to edges of plate a . The back b is also a grater; but it is intended to cut articles of a coarser nature—such as turnips, cabbage, and 30 the like. For this purpose the plate b is provided with a series of preferably semicircular holes, having on their lower curved side outwardly and upwardly extending cutting-edges c , and on the upper straight side downwardly

and inwardly extending guide-plates d . The 35 handle e is preferably made in one piece with back b . At the lower end the back b , and preferably also plate a , is made concave or cut away, so as to form the two legs f , as shown.

When the grater a is used, the grated articles will roll down along the surface of the same in the usual manner; but when grater b is employed the large pieces cut off will fall through the holes between the two plates a b . The guide-plates d will feed such pieces 45 downward and prevent them from falling upon and clogging grater a . As the pieces cut off fall upon the table upon which the grater is placed, they will be exposed to view and pass out from between the plates a b through the 50 lower cut-away portion between legs f .

I claim as my invention—

1. As a new article of manufacture, a grater composed of an indented convex plate, a , and an indented straight plate, b , said plates being 55 provided with cutters of different fineness, substantially as specified.

2. The combination of indented convex plate a with indented straight plate b , the plate b having upwardly and outwardly projecting cutting-edges c and inwardly and downwardly extending guide-plates d , and having cut-away 60 lower end, substantially as specified.

H. BLOCH.
